Primary Examiner — Terry A Wallace(74) *Attorney, Agent, or Firm* — McHale & Slavin, P.A.(57) **CLAIM**

The ornamental design for a roll top backpack cooler, as shown and described.

DESCRIPTION

FIG. 1 is a front right isometric view of the roll top backpack cooler of the present invention;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a right rear bottom isometric view thereof;

FIG. 9 is a top front right isometric view thereof illustrating the roll top backpack cooler in an open position; and, FIG. 10 is a top rear left isometric view thereof illustrating the roll top backpack cooler in an open position.

The portions of the roll top backpack cooler illustrated in broken lines form no part of the claim for the roll top backpack cooler.

1 Claim, 10 Drawing Sheets(56)
